UNITED STATES PATENT OFFICE.

ADOLPH A. THOMAS, OF NEW YORK, N. Y.

PHONOGRAPHIC REPRODUCING APPARATUS.

Application filed July 28, 1926. Serial No. 125,337.

My invention relates to the art of reproducing recorded sound, and one of its objects is to provide a phonograph or similar acoustic machine with novel reproducing mechanism adapted to reproduce either mechanically through the tone arm or electrically through a loudspeaker unit connected to the horn. The reproducing mechanism comprises selecting means which place either 10 method of reproduction within ready control of the operator.

Another object of my invention is to provide a phonograph with mechanical and electric reproducing means selectively operable independently of each other, in combination with valve mechanism automatically controlled by the operative condition of each reproducing means to connect the operative reproducing means with the amplifying apparatus of the machine. In order to explain this feature of my invention, I have shown it in connection with an electro-mechanical reproducer having means for manually adjusting the same for either type 25 of reproduction. This adjusting or selecting means automatically operates a valve for placing either the tone arm or a loudspeaker unit in acoustic communication with the amplifying horn of the phonograph. 30 The loudspeaker unit, which is a form of telephone receiver, is connected to a branch tube or passage arranged to communicate with the horn at a suitable point. A valve is so mounted that in one position it opens 35 the horn to the tone arm and closes off the branch tube; in the other position, the valve opens communication between the branch tube and the horn, while at the same time preventing sound waves from passing into 40 the tone arm. A suitable electromagnetic device operates the valve, and this mechanism is automatically controlled by the operative condition of the reproducer. When 45 the diaphragm is selected for mechanical reproduction through the tone arm, a circuit is automatically closed through the valve-actuating device to move the valve into position for connecting the tone arm with the horn and shutting off the branch tube. On 50 the other hand, when the selecting means is operated for electric reproduction, the valve-actuating device automatically moves the valve into position to connect the loudspeaker unit with the horn and cut off the tone arm, so that the sound waves produced

by the loudspeaker diaphragm are amplified through the horn.

In the preferred embodiment of my invention, the connection between the loudspeaker unit and the horn is concealed below the top 60 board of the cabinet. The actuating device for the valve is, therefore, out of sight. Indeed, so far as the operator is concerned, the controlling valve does not exist, for its operation is wholly automatic. 65

The selecting means of my double-acting reproducer may also control a circuit of the electric reproducing mechanism. That is to say, when the diaphragm is reproducing, the electric reproducer circuit is open; when the 70 selecting means is operated for electrical reproduction, the reproducing circuit is automatically closed. This makes the use of a separate switch for the electric reproducing mechanism unnecessary, and absolutely prevents waste of current when the electric reproducer is not in operation. 75

In order to explain my invention I have selected an illustrative embodiment thereof for detailed description, it being understood 80 that the construction shown in the accompanying drawings is merely by way of example and not as a limitation or restriction. In these drawings,

Fig. 1 illustrates an interior face view of 85 an electro-mechanical reproducer embodying my invention, certain parts being shown in section on line 1-1 of Fig. 2;

Fig. 2 is a cross-section on the broken line 2-2 of Fig. 1, showing the needle arm connected to the diaphragm; 90

Fig. 3 is a transverse cross-section on line 3-3 of Fig. 1;

Fig. 4 shows a view (partly broken away) 95 similar to Fig. 3, with the connection between the diaphragm and the needle arm broken;

Fig. 5 is an inside view of the cover plate (partly broken away), showing the mounting of the switch contacts for the valve-controlling circuits and the reproducer circuit; 100

Fig. 6 is a fragmentary face view of the outer casing to indicate how the selecting knob should be turned for obtaining electric or mechanical reproduction; 105

Fig. 7 represents a side view of a phonograph cabinet equipped with my double-acting reproducer and the automatic valve control;

Fig. 8 is a cross-section on line 8-8 of 110

Fig. 7, showing a front view of the valve-operating mechanism, the parts being in position for electrical reproduction;

Fig. 9 shows the valve-operating mechanism (partly in section) on an enlarged scale, the parts being in position for mechanical reproduction;

Fig. 10 illustrates an inside cross-sectional view of a preferred form of valve mechanism, the valve disks being in position for mechanical reproduction;

Fig. 11 is a cross-section on line 11—11 of Fig. 10;

Fig. 12 is a diagrammatic view showing the circuit connections of the valve-controlling mechanism when the diaphragm is used for reproduction; and

Fig. 13 is a view similar to Fig. 12 showing the valve-controlling circuit connections when the electrical reproducer is in operative condition.

In order to make the drawings as clear as possible, I have purposely exaggerated the dimensions and relative proportions of the different parts, which have been spread out considerably more than would be necessary in actual practice. These drawings are therefore not to be taken as shop drawings.

A suitable casing C houses the various parts that comprise the interior working mechanism of the instrument. The casing C is here shown as consisting of a back plate 1, a cylindrical body section 2, and a front plate or cover 3. These three parts may be separately connected, as by screws 4 engaging in peripheral bosses 5 of section 2. The casing may be constructed of non-magnetic metal, such as brass, aluminum, or aluminum alloy, or it may be shaped out of suitable composition material. The body section 2 is provided with a transverse annular flange 6 arranged to form a shallow recess or chamber 7, in which is mounted an acoustic diaphragm 8. This diaphragm is held rigidly clamped at its periphery in any practical way. For simplicity, I have shown diagrammatically a pair of non-metallic rings 9 between which the diaphragm is held for vibratory movement. The diaphragm is easily inserted in position through the open mouth of recess 7 before the back plate 1 is screwed on.

A magnet M, preferably of the permanent type, is supported within the casing. In the present instance, the magnet is secured to the annular flange 6 by screws 10 or otherwise. The flange 6 thus performs the double function of supporting the magnet and serving as part of the mounting for the diaphragm. By making the magnet of circular shape, as shown in Fig. 1, it is possible to obtain a maximum length of magnetic path in a small cylindrical casing. The ends of magnet M are turned forwardly at 11 for giving pole pieces 12 of soft iron. These

pole pieces are preferably cylindrical and are arranged in axial alignment to provide an airgap 13.

A needle arm 14 is pivotally mounted on casing C by any practical means. For convenience, I have shown the casing provided with a pair of lugs 15, between which is supported a spring blade 16 of proper strength and resiliency. This spring passes through (or is otherwise rigidly connected to) the needle arm near the outer end thereof, which constitutes a needle holder 17. The tension of spring 16 permits the needle arm to vibrate transversely of the casing, as about a pivot, and the strength of the spring is amply sufficient to take up the longitudinal thrust on the needle arm in the playing of a record. The spring blade 16 thus serves as a pivot support for the needle arm and as a restoring or centering spring for the same.

Any other suitable support for the needle arm may be employed. A slot 18 in section 2 of the casing permits the insertion of the needle arm into the casing and allows free vibration of the arm. It goes without saying that, when I refer to the lever 14 as a needle arm, I mean any suitable member for carrying a record-playing stylus, which may be in the form of a pointed needle for lateral-cut records, a tiny sapphire ball for vertical-cut records, a diamond point for Edison records, or any other practical form.

To the inner end of the needle arm 14 is rigidly connected a coil 19, as by means of a strap or band 20 clamped tight around the coil. The ends of strap 20 are secured by a screw or rivet 21 to the needle arm. The coil is arranged to vibrate in the air-gap 13 of the magnet. In the normal position of the needle arm, the coil 19 is substantially in axial alignment with pole pieces 12. The internal diameter of the coil should preferably be about the same as the diameter of the pole pieces. As the needle arm 14 vibrates, the coil 19 vibrates transversely of the pole pieces and thereby cuts the magnetic lines of force to generate electrical current impulses. This will be understood by those skilled in the electrical art without the need of further explanation. By connecting the coil in suitable circuits, these current impulses can be utilized to operate a loud-speaker or any other reproducing device. It is clear from Figs. 1 and 2 that the needle vibrations are transmitted to the coil in amplified ratio, so that the smallest vibrations of the needle point are sufficient to generate current impulses in the circuit of the coil. It is to be noted that there is no magnetic drag or load on the needle arm during vibration of coil 19.

In the broad aspect of my invention, the magnet M and coil 19 represent merely one of many practical forms of electric reproducing mechanism operated or controlled by

the vibrations of the needle arm. I do not, therefore, intend to be limited to any particular construction of electric reproducing means, provided it is capable of operation independently of the diaphragm. One of the important features of my invention lies in the fact that the electric reproduction takes place without the diaphragm, which is used solely for mechanical reproduction through the tone arm on which the reproducer is mounted. To accomplish this result, I provide a readily separable and restorable connection between the diaphragm and the needle arm. This fundamentally novel idea may be mechanically carried out in various ways, one of which is shown by way of example in Figs. 1-4.

The diaphragm 8 is provided at the center with a screw-plug 22. The needle arm 14 has rigidly secured to it a screw-threaded socket 23 in which is supported a screw 24 provided at its outer end with a pinion 25. The screw 24 is adapted to engage in the screw-threaded plug 22. On the front plate or cover of the casing is formed a bearing 26 in which is journaled an arbor or stub-shaft 27. A suitable finger piece 28, here shown as a knob, is fixed to the outer end of shaft 27, and to the inner end of this shaft is connected a gear 29 arranged to mesh with pinion 25. The gear 29 does not have a complete circle of teeth, but has a cut-away or mutilated section 30 which does not engage the pinion 25, for a purpose that will presently be explained. A fixed stop 31 on the casing engages a stop 32 on gear 29 to limit the movement of the latter in either direction.

The operation of the selective mechanism above described is as follows: Let us assume that the screw 24 is in engagement with plug 22 of the diaphragm, so that the needle arm is operatively connected with the diaphragm for mechanical reproduction. This is the position of the parts shown in Figs. 1, 2 and 3. It will be observed that the gear 29 is out of contact with the pinion 25 of connecting screw 24, thus permitting free vibration of diaphragm and needle arm as a single member without interference by the controlling gear. Now, if the operator desires electric reproduction, the knob 28 is turned in the direction indicated by arrow *a* in Fig. 6. After a slight preliminary turn, the teeth of gear 29 engage the pinion 25 and rapidly rotate the screw 24 in a clockwise or right-handed direction. The screw 24 being left-handed, this turning of the screw moves the same out of plug 22 to disconnect the needle arm from the diaphragm. When the lug 32 on gear 29 strikes one side of the fixed stop 31, the screw 24 is in the position shown in Fig. 4 and further movement of the knob 28 in the direction *a* is prevented. By providing an opening 33 in the

cover of the casing in alignment with pinion 25, the width of the casing may be reduced without danger of the pinion striking the casing when the needle arm vibrates. The pinion 25 is long enough to permit continued engagement with gear 29 during the axial movement of screw 24 from its connecting position in Fig. 3 to its withdrawn position in Fig. 4. To connect the needle arm again with the diaphragm, the knob 28 is turned in the direction of arrow *b* in Fig. 6, whereby the pinion and screw are rotated counterclockwise until the lug 32 of gear 29 strikes the other side of stop 31. The screw 24 is then in the connecting position shown in Fig. 3, and the gear 29 is fully disconnected from the pinion. It may be found desirable to insert a pad 34 of hard rubber or other yieldable material in the bottom of plug 22 to produce a final jamming effect as the screw 24 reaches home and presses against the pad. This makes a tight solid joint between diaphragm and needle arm, and yet it is a joint that is easily separated by a mere turn of knob 28. To prevent possible rattling or looseness of screw 24 when it is in disconnecting position, the socket 23 may be provided with a lining 35 of hard rubber or like material, which presses into the screw-threads and thereby holds the screw against working loose during the vibrations of the needle arm. It is understood that the gear ratio between the members 25 and 29 is so related to the pitch and number of screw-threads in screw 24 that one turn of gear 29 moves the screw into and out of connecting position. I have not attempted to indicate these transmission ratios with mathematical precision in the drawings.

The operator can readily tell, by simply feeling the knob 28, whether the diaphragm and needle arm are connected or disconnected. For instance, looking at Fig. 6, if the operator tried to turn the knob clockwise and found it locked against movement in that direction, he would know at once that the needle arm was connected to the diaphragm and that, therefore, the instrument was in condition for mechanical reproduction. Conversely, if the operator found that he could not turn the knob in the direction of arrow *a* in Fig. 6, he would know that the instrument was set for electric reproduction.

So that no unnecessary waste of battery current may occur during intervals in which the electric reproducing mechanism is not used, I provide means for automatically opening suitable switch connections in the electric reproducer circuit when the instrument is operated for mechanical reproduction through the diaphragm. In the present embodiment I have shown a pair of switch contacts 36 and 37 mounted on an insulating plate 38, which is secured to the inside of

cover 3, or is otherwise supported in the casing. These contacts are in the form of movable spring arms normally out of engagement with each other. To the contacts 36 and 37 are connected the end conductors 39 of coil 19. Also, a pair of leads are connected to contacts 36 and 37. The selecting member 29 carries an insulated cam projection 40 arranged to engage the spring contact 36 and force it against the contact 37 when the member 29 disconnects the needle arm from the diaphragm, as shown in Fig. 13. It is understood, of course, that the finger piece 28 is not moved into the "electric" position unless and until the instrument is to be used for electric reproduction. The cam 40 does not close the contacts 36 and 37 when the selecting member 29 connects the diaphragm and needle arm, as may be seen from Fig. 12, because the member 29 is not in exactly the same position when the diaphragm is connected as when it is disconnected. This is due to the fact that the lug 32 engages opposite sides of stop 31, which has a predetermined thickness. In the broader aspect of my invention, the contacts 36 and 37 represent a switch in any part of the electric reproducing circuit or system of which the coil 19 is an element.

30 The reproducer casing C is operatively mounted on a tone arm 41, as by means of a hub 42 projecting from the back plate 1 of the casing. A set-screw 43, engaging in a slot 44 of hub 42, determines the correct position of the reproducer on the tone arm. The coil leads may be connected to binding posts on the back plate of the casing, as will be understood without illustration.

40 I now come to that feature of my invention which has to do with means for automatically controlling an acoustic valve in accordance with the operative condition of the reproducer. The phonograph cabinet has an amplifying horn or chamber 45 in connection with tone arm 41. The inner portion of the horn is here shown as a neck 46 having an extension 47, which preferably extends downwardly at an acute angle to the vertical axis of the neck. The tubular parts 46 and 47 are preferably cast or molded from metal or composition material as a single piece fitting tightly between the connecting members 48 and 49. On extension 47 is mounted a branch tube 50 carrying a loud-speaker unit 51 of suitable construction. It will be understood that the telephone unit 51 is operated or controlled by the electric impulses generated in coil 19. The circuit connections between the electric reproducer and the telephone receiver 51 need not be shown or described, for they will be clear to those familiar with this art. The cabinet may have a door 52 in the side for easy insertion or removal of unit 51.

50 In casting 46-47 is mounted a valve,

which in this instance comprises a pair of valve disks 53 and 54 mounted centrally on pivoted rods 55 and 56. Set screws 57, or any other suitable means, hold the valve disks against turning relatively to the supporting rods, which are journaled at diametrically opposite points in casting 46-47. In assembling the valve mechanism, the disks 53 and 54 are inserted one at a time into the casting before the latter is connected with the parts 48, 49 and 50. Assuming the valve disk 53 held in proper position, the supporting rod 55 is threaded through the central hole in the disk and a screw driver is then inserted through the open end of extension 47 to tighten the set screw. The valve disk 54 and rod 56 are assembled in the same way.

It will be seen from Fig. 10 that the valve disks 53 and 54 are mounted in parallel relation. When the disks are in the position shown in full lines in Fig. 10, the tone arm 51 is fully open to the horn and the branch tube 50 is completely closed from the horn by valve disk 54. When the disks are moved into the positions indicated by dotted lines 53' and 54', the tone arm is entirely shut off from the horn, and the branch tube 50 communicates freely with the horn. The disk 53 in closing position 53' forms a continuation of extension 47, so that sound waves pass easily from tube 50 into the horn without a right-angled turn, whereby the reproduction is improved. When either valve disk is in open position, it stands in a plane substantially parallel with the axis of the tubular member in which it is mounted, and the disk therefore does not interfere with the passage of sound waves, especially since the disks may be made very thin (of aluminum, for instance). The particular shape of the valve disks will obviously depend on the shape of the conduits 46 and 47. In the present embodiment, these conduits are cylindrical, and so the valve disks are elliptical or oval.

On the neck 46 of the horn is fixed a bracket 58, which carries a solenoid indicated as a whole by S. This solenoid comprises a pair of coils 59 and 60 mounted in axial alignment, and a magnetic core or plunger 61. The coils are held rigidly on a tube 62 between a pair of end plates 63. The tube 62 acts as a support and guide for the reciprocable core 61. The ends of coils 59 and 60 lead to terminals or binding posts 64 and 65, respectively, which are properly connected in the circuit of a battery 66, or other source of electric current for energizing the coils.

On the outer end of rod 55 is fixed a lever comprising arms 67 and 68, the latter being longitudinally slotted at 69. The outer end of rod 56 carries an arm 70, which is connected to arm 67 by a link 71, whereby those two arms always move together in

parallel relation. The solenoid core 61 is provided with a nonmagnetic extension 72, which has a pin 73 arranged to engage in slot 69 of arm 68. A coil spring 74 is connected at one end to a pin or stud 75 on neck 46, and at the other end to the arm 68 at the point 76. The normal tendency of spring 74 is to contract and thus to rock the pivoted lever 67-68 (and therefore the rod 55 and valve disk 53) in the direction of movement of the solenoid core 61, as will presently be explained.

In the circuit of coil 59 is a pair of contacts 77, and the circuit of coil 60 includes a similar pair of contacts 78. These pairs of contacts are mounted in fixed position within casing C at different distances from the center of shaft 27. For convenience, I have shown each pair of contacts mounted on a small insulating block 79 carried by the casing cover 3. The selecting wheel 29 carries two arc-shaped contact strips 80 and 81. In Figs. 3 and 4, these strips are shown as pieces of spring metal set firmly into slotted insulating blocks 82 secured to wheel 29. On referring to Fig. 12, it will be seen that contact piece 80 is so arranged as to connect contacts 77 of coil 59 when the wheel 29 reaches a predetermined position in its movement to connect the needle arm 14 with diaphragm 8. Contact piece 81 is so arranged that, when the wheel 29 is turned counterclockwise to place the electrical reproducer in operative condition, the contacts 78 are closed just shortly before the wheel reaches final position. It should be noticed that the contact piece 80 never touches contacts 78, and the other contact piece 81 at no time engages contacts 77.

The valve-controlling operations that automatically take place when the selecting member 29 is actuated are as follows, reference being had to Figs. 12 and 13: It will be remembered that the diaphragm is connected to the needle arm when the member 29 is turned clockwise (as viewed in Figs. 1 and 12). In the position of the parts as illustrated in Fig. 12, the member 29 is being turned in the direction of arrow *c* and is near the end of its movement. The contact piece 80, carried by member 29, now connects the switch contacts 77 and the circuit through coil 59 is closed. The energized coil draws the magnetic core 61 into the position shown in Fig. 9, whereby the pivoted lever 67-68 is rocked clockwise (as viewed in Fig. 9) to move the valve disks into the position indicated in Fig. 10. That is to say, the tone arm 41 is now acoustically connected with the horn and the branch tube 50 is cut off. Referring back to Fig. 12, as the operator continues to rotate the selecting wheel 29, the contact piece 80 moves out of engagement with contacts 77 and the circuit of coil 59 is broken. This prevents a use-

less consumption of current during the operation of the phonograph. The valve disks, however, remain in actuated position, being firmly held therein by the spring 74. When the lug 32 on member 29 strikes the fixed stop 31, the member 29 is in its final position, as previously explained. The position of contact piece 80 at that time is indicated by the dotted lines 80', while the final position of contact piece 81 is at 81'.

Let us now suppose that we want to place the electric reproducer in operative condition. The selecting member 29 is turned in the direction of arrow *d* in Fig. 13. Near the end of the movement of member 29, contact piece 81 bridges the contacts 78 and the circuit through coil 60 is closed, as indicated in Fig. 12. The core 61 is drawn into the coil and lever 67-68 is rocked counterclockwise into the position shown in Fig. 8, whereby the valve disks are actuated into the position indicated by dotted lines 53' and 54' in Fig. 10. The tone arm is now closed off from the horn and the telephone receiver 51 is in acoustic communication with the horn through branch tube 50. As the member 29 is turned to its final position in the direction of arrow *d* in Fig. 13, the contact piece 81 leaves the contacts 78 and the circuit through coil 60 is interrupted. The final position of contact piece 81 is indicated at 81' in Fig. 13.

The foregoing description makes it clear that when the operator turns the finger piece 28 to place either the diaphragm or the electric reproducer in operative condition, the acoustic valve 53-54 is automatically operated into correct position. The action of the solenoid S is supplemented by spring 74, which moves the lever 67-68 into final position independently of core 61 and holds it there.

I have previously described how the circuit of reproducer coil 19 is automatically closed when the selecting member 29 is moved into position for electric reproduction, and how that circuit is automatically opened when mechanical reproduction takes place. Instead of controlling the switch contacts 36 and 37 of coil 19 directly by the selecting member 29, the reproducer circuit may be controlled by the movement of the valve-operating mechanism. This idea can be embodied in various ways. In Fig. 9 I have shown a pair of contacts 36' and 37' mounted on an insulating plate 82' carried by the extension 47. These contacts, like contacts 36 and 37 previously described, form a normally open switch in a circuit 83 of the electric reproducer mechanism. When the valve disks 53 and 54 are actuated into the position 53' and 54' (see Fig. 10), the arm 70 strikes the spring contact arm 36' and forces it against contact 37', thereby closing reproducer circuit 83. When the

valve disks are operated to close tube 50 and open the tone arm for mechanical reproduction, the spring contact 36' by virtue of its initial set automatically breaks the circuit. Any other practical construction and arrangement of switch may be employed for automatic operation by the valve-controlling mechanism.

Although I have shown a valve consisting of two disks, a single valve member may be used. For example, a valve plate could be pivoted at the point 84 in Fig. 10, so that it could swing between the positions 53' and 54. In that event, however, the parts 46 and 47 must be of a shape to allow swinging movement of the valve. Various other changes and modifications will occur to those who are skilled in this art, without departing from the scope of the invention as defined in the following claims. In the basic scope of my invention as regards the automatic valve control, the mechanical and electrical reproducing means need not be mounted in a single casing, but may be separate devices properly mounted on the tone arm.

This application is in part a division of my copending case Serial Number 84,551, filed January 29, 1926.

What I claim as my invention is:

1. A phonograph having mechanical and electrical reproducing means adapted to be operated independently of each other, a horn for amplifying the sound vibrations of both reproducing means, and valve mechanism automatically controlled by the operative condition of each reproducing means to connect the operative reproducing means with said horn.

2. In phonographic reproducing apparatus, the combination of a horn, mechanical and electrical reproducing means adapted to be operated by a record-playing needle independently of each other, acoustic connections whereby the vibrations of both reproducing means are transmitted through said horn, means for placing either of said reproducing means in operative condition, and mechanism automatically operated by said last-mentioned means for so controlling said acoustic connections that the reproducing means in operation is connected with said horn while the inactive reproducing means is acoustically disconnected from the horn.

3. In phonographic reproducing apparatus, the combination of a horn, two sound conduits communicating with said horn, a valve for controlling the acoustic connection between each conduit and said horn, a mechanical reproducer connected with one of said conduits, a telephone receiver connected with said other conduit, an electric reproducer operable independently of said mechanical reproducer and electrically connected with said receiver, electromagnetic mechanism for actuating said valve to open

communication between the horn and that conduit through which reproduction takes place, said valve closing the other conduit, and means for automatically controlling said mechanism in accordance with the operative condition of each reproducer.

4. In phonograph reproducing apparatus, the combination of a horn, a tone arm communicating with said horn, mechanical and electrical reproducing means mounted on said tone arm, a telephone receiver connected with said horn and included in a circuit of said electrical reproducing means, a valve arranged to control the acoustic communication of said tone arm and said receiver with said horn, means for placing either of said reproducing means in operative condition, and electromagnetic mechanism controlled by said last-mentioned means for actuating said valve into such position that sound waves initiated by the reproducing means in operation are conveyed through the horn.

5. In phonograph reproducing apparatus, the combination of a horn, a tone arm and a branch tube communicating with said horn, a reproducer unit mounted on said tone arm and having a diaphragm and electric reproducing mechanism operated by a record-playing needle, means for selecting either said diaphragm or said mechanism for reproducing operation, a telephone receiver connected to said branch tube and included in a circuit of said reproducing mechanism, a valve arranged to control the connections of said tone arm and said receiver with said horn, an electromagnetic device for actuating said valve to place either said tone arm or said branch tube in communication with the horn, and switch connections controlled by said selecting means for actuating said valve into such position that sound waves initiated by the reproducing means in operation are conveyed through the horn.

6. In phonographic reproducing apparatus, the combination of a horn, a pair of tone arms communicating with said horn, a valve for controlling the communication between said tone arms and said horn so that only one tone arm at a time is operatively connected with the horn, means for reproducing mechanically through one of said tone arms, means for reproducing electrically through the other tone arm, both of said reproducing means being operable by a record-playing needle independently of each other, and means for automatically actuating said valve when either of said reproducing means is placed in operative condition, said automatic actuating means causing the valve to connect the reproducing tone arm with the horn and to shut off the other arm.

7. In phonograph reproducing appara-

- tus, the combination of a horn, a tone arm communicating with said horn, a reproducer mounted on said tone arm, said reproducer comprising a casing containing a diaphragm 5 and electric reproducing means, said diaphragm transmitting sound vibrations through said horn, a telephone receiver controlled by said electric reproducing means and acoustically connected with said horn, 10 an adjustable finger piece outside said casing for placing either said diaphragm or said electric reproducing means in operative condition, and mechanism controlled by said finger piece for placing either said diaphragm or said receiver in communication with said horn.
8. In a phonograph, a horn having a neck communicating with a tone arm, a branch tube connected obliquely to said neck and adapted to communicate with an electric reproducer, a valve member for controlling the acoustic connection between said tone arm and the horn, a second valve member for controlling the acoustic connection between said branch tube and the horn, means for so mounting and connecting said valve members that when one is open the other is closed, said first valve member when closed lying obliquely across said neck to form a 25 continuation of said oblique branch tube, whereby sound waves pass easily from said tube into the horn without a right angled turn, and means for simultaneously operating said valve members.
9. In a phonograph, a horn having a neck communicating with a tone arm, a branch tube connected obliquely to said neck and adapted to communicate with an electric reproducer, a valve member for controlling the acoustic connection between said tone arm and the horn, a second valve member for controlling the acoustic connection between said branch tube and the horn, means for so mounting and connecting said valve members that when one is open the other is closed, said first valve member when closed lying obliquely across said neck to form a continuation of said oblique branch tube, whereby sound waves pass easily from said tube into the horn without a right-angled turn, and electromagnetic means mounted on said horn for simultaneously operating said valve members.
10. In a phonograph, a horn having a neck arranged to communicate with a tone arm, a branch tube connected to said neck and adapted to communicate with an electric reproducer, a pair of valve members for controlling the acoustic connections of said tone arm and said tube with said horn, said valve members being so mounted that when one is closed the other is open, so that either said tone arm or said tube communicates with said horn, a coil for actuating said valve members into one position, 45 a second coil for actuating said valve members into the other position, means for releasably holding the valve members in either actuated position, and means for controlling the circuit of each coil.
11. A phonograph having mechanical and electrical reproducing means adapted to be operated independently of each other, a horn for amplifying the sound vibrations of both reproducing means, valve mechanism to connect one or the other of said reproducing means with said horn, an electromagnetic coil controlled by the operative condition of said mechanical reproducing means for actuating said valve mechanism to connect said 50 mechanical reproducing means with said horn, and a second electromagnetic coil controlled by the operative condition of said electrical reproducing means for actuating said valve mechanism to connect said 55 electrical reproducing means with said horn.
12. In a phonograph reproducer having a casing, a diaphragm provided at the center with a screw-threaded lug, a needle arm having an adjustable screw adapted to fit into said lug for rigidly connecting the diaphragm to the arm, and a rotary member projecting outside said casing for turning said screw into and out of engagement with 60 said lug, said member being automatically disconnected from said screw after the latter has been adjusted into the desired position.
13. A phonograph having mechanical and electrical reproducing means adapted to amplify through a horn, a valve for controlling the acoustic connection of each reproducing means with said horn, and a reproducer circuit automatically controlled in accordance with the position of said valve.
14. A phonograph having mechanical and electrical reproducing means adapted to amplify through a horn, a valve for controlling the acoustic connection of each reproducing means with said horn, means for actuating said valve into proper connecting position for either mechanical or electrical reproduction, and a reproducer circuit controlled by said valve-operating means.
15. A phonograph having mechanical and electrical reproducing means adapted to amplify through a horn, a valve for controlling the acoustic connection of each reproducing means with said horn, electromagnetic means for actuating said valve into proper connecting position for either mechanical or electrical reproduction, and a spring for positively actuating said valve into final position independently of said 120 electromagnetic means, said spring holding the valve in final position.
16. A phonograph having mechanical and electrical reproducing means adapted to be operated independently of each other, a horn 125

for amplifying the vibrations of both reproducing means, valve mechanism to connect one or the other of said reproducing means with said horn, electromagnetic means for actuating said valve mechanism into either connecting position, means for automatically opening the circuit of said electromagnetic means when the valve mechanism has been actuated, and means independent of 10 said electromagnetic means for holding the valve mechanism in actuated position.

17. A phonograph having a horn and a tone arm, a mechanical reproducer mounted

on said tone arm and adapted to amplify through the tone arm and horn, electrical 15 reproducing mechanism operated by a record-playing needle and acoustically connected with said horn, and means for automatically controlling the acoustic connections of said mechanical reproducer and said 20 electrical reproducing mechanism with said horn in accordance with the operative condition of said mechanical and electrical reproducing devices.

ADOLPH A. THOMAS.
